TOOTH BRUSH

Elmer E. Hachman, Baltimore, Md.

Application November 21, 1935, Serial No. 50,842

7 Claims. (Cl. 15—176)

This invention relates to tooth-brushes, and especially to an assembly or arrangement of adjustable and interchangeable brush-heads in conjunction with a handle and a shank which are 5 of novel and useful design or shape and on which the brush-heads are normally offset or laterally disposed with respect to the longitudinal lines of the handle and shank.

One object of this invention is to provide a 10 tooth-brushing arrangement that is capable of being transformed into different shapes so as to conform to the various and varying conditions in the dental arrangements in the mouths of different people, and the changes that take place in the 15 mouth of nearly every individual; for instance; differently shaped and differently arranged teeth; the instances where teeth have been extracted, leaving sore gums that it is desired to avoid brushing while brushing the teeth that need brushing; 20 and the instances where artificial dentures are permanently secured on mouths of persons who wish to gain ready and convenient brushing contact with the surfaces adjacent to the gums, and to clean out spaces under the dentures.

Another object is to provide an offset duplex tooth-brush which is held in horizontal position at all times when in use, in contradistinction to the ordinary or usual form of tooth-brush which must be operated in an inclined position when 30 the user's head is erect or untilted, oft times resulting in spilling tooth-washing liquid and saliva on clothing etc.; whereas, when the offset tooth-brush is operated (with the head erect and the tooth-brush horizontal) there is no depressing 35 of the lower lip for permitting the liquid to escape.

Another object is to provide an offset tooth-brush-head with attaching means for removably securing it in place opposite another of its kind 40 so that, when desired, the upper and lower sets of teeth can thereby have their posterior surfaces brushed simultaneously.

Another object is to provide a tooth-brushing arrangement that includes an offset brush-head 45 at its opposite ends so that it may be operated in opposite sides of the mouth alternately without reversing it.

Another object is to provide a tooth-brush with one or two brush-head-bases that are provided 50 with openings in their opposite edges to receive and hold securing projections in the lateral edges of the brush-heads, so the latter can be interchangeably engaged with the respective sides of the brush-head-bases for the sake of variety of 55 sizes and shapes and positions of the brush-heads

to be used with any unit that comprises the handle, shank and brush-head-base.

Another object is to provide the brush-head-bases with means to receive the respective brush-heads in differently adjusted positions along the 5 edges of the brush-head-bases so as to compensate for varying shapes, positions and conditions of teeth, dentures, etc.

Other objects, purposes, characteristics and 10 important features are pointed out or implied in the following details of description, in connection with the accompanying drawing in which,—

Fig. 1 is an elevation of the working face or side of a tooth-brush assembly or arrangement that constitutes one embodiment of this invention. 15

Fig. 2 is a view as seen from the opposite side of Fig. 1, the end portions being in section along the line 2—2 of Fig. 3.

Fig. 3 is a lower edge view, as considered in connection with Fig. 2. 20

Fig. 4 is a modified form that includes differently formed brush-head-bases at its opposite ends, the right end being in section for showing the sliding connectors and the holes that receive them interchangeably, the broken lines 25 showing how the brush-head can be moved to different adjustments.

Fig. 5 is a sectional view showing a tapered brush-head-base between two slightly removed brush-heads in positions to become engaged with 30 the brush-head-base when moved towards the latter, the lower brush-head having its studs nearer one end than the other, so its adjustment is effected by reversing it or by interchanging from one side to the other side of the brush-head-base. 35

Fig. 6 is a sectional view showing tongue and groove connections between the brush-heads and the brush-head-base, this showing that I do not limit my invention to any particular single form 40 of sliding frictional securing means for the brush-heads.

Fig. 7 is a sectional view taken along the line 7—7 of Fig. 6. 45

Fig. 8 is an inner edge view of either one of the brush-heads shown in Figures 6 and 7, showing a split and spread end of the dovetail rib, constituting spring-frictional securing means.

Fig. 9 is a perspective view of a split springy stud 50 such as may be used in lieu of any one of the studs (or all of them) such as shown in Figs. 2, 4 and 5.

Fig. 10 is a transverse sectional view showing how any or all forms of the invention may have 55

the brush-heads arranged angularly, at different angles, with respect to the brush-head-base.

Referring to this drawing in detail, wherein, similar reference numerals refer to similar parts 5 in the several views, the invention is described in detail as follows:

The main unit or handle member consists of the handle 1a or 1b, shanks 2a or 2b or 2c, and brush-head-bases 3, 3a, 3b, 3c, 3d, 3f or 3g. The 10 right-end brush-head-base 3a may also be properly considered as a brush-head, being provided with bristles 4 as are the brush-heads 5a, 5b, 5c, 5d, 5e, 5f, 5g and 5h. The left-end brush-head-base, however, is free from bristles and may be 15 used, alternately with that which has bristles, to carry an offset brush-head of one of the various kinds referred to (or other kinds not here shown); for there are dental-conditions where the co-operation of two sets of bristles is desirable, and 20 other dental conditions that call for use of a brush on certain teeth or dentures that are adjacent to tender or diseased gums to be untouched while brushing the teeth.

The main purpose of offsetting the brush-heads 25 is to gain free, easy and unobstructed brushing access to the posterior and lingual surfaces of the sets of teeth in the user's mouth. When brushing teeth with these offset brush-heads (including bristles), there is a tendency for the handle 30 to turn in the hand of the user; so the handle is made relatively thin, wide and long to offset the turning tendency by a slight gripping pressure of the thumb and fingers of the user's hand. This turning tendency is also offset, or overcome in 35 part, by forming the shanks in a compound curve, as shown; so the plane of the handle lies substantially in the same plane with the free ends of the bristles 4; the plane of the handle meaning the plane that lies in the length and breadth 40 of the handle. Moreover, this curving of the shanks provides easier working or brushing access of all the bristles to the surfaces to be cleaned.

Persons who consider the importance of time-saving, and who wish to brush the upper and 45 lower sets of teeth simultaneously, can accomplish the same by employing the brush-heads in bi-lateral relation as indicated at the right end of Fig. 1 and at both ends of Fig. 4; and when thus used, advantages may be obtained by having the brush-head-bases and brush-heads angular or outwardly tapering as shown at 3b, 3c, 5b and 5c, or by having only the one or the other (brush-head-base or brush-head) tapered, as is 50 shown in Fig. 6. When a person's mouth is open, the upper and lower sets of teeth are inwardly inclined towards one another, being relatively close 55 together at points farthest posterior where the assembly 3c—5b—5b is narrowest when used in brushing these posterior teeth; but when thus used, the widest part of the assembly is in brushing contact with the more widely spaced teeth of the inclined sets.

For most thoroughly cleaning the teeth and 60 massaging the gingivae or gums, the unilateral assembly or arrangement is preferable to the bi-lateral arrangement; and in order that the operation of the unilateral assembly may be thoroughly understood, the handle-member may be considered as having two axes, viz., the longitudinal axis and the transverse axis. The longitudinal axis is that about which the device is turned from the position shown in Fig. 1 to that shown in Fig. 2 without reversing the ends. The transverse 65 axis is that which passes through or across the

middle part of the handle, and about which the device is turned in reversing its ends. In brushing the outer surfaces of the upper set of teeth, the device as shown in Fig. 1 is held in the user's hand, and the brush-head 5a at the right-hand end is used in the right side of the mouth and against the upper set of teeth and against the outer surfaces thereof; next, the device is turned about its transverse axis to bring the left-hand end into the left side of the mouth wherein the 10 brush-head at the left engages with the outer surfaces of the upper set of teeth; then, to gain brushing access to the inner or lingual surfaces of the upper teeth, it is necessary to turn the device about its transverse axis to the reversed 15 (end for end) position where the bristles project away from the user. Continuing the use of the device after brushing the upper teeth, it will be seen that the device may now be rotated on its longitudinal axis so as to turn the brush-heads 5a 20 downward, and as the bristles will then extend towards the user, they are brought into contact with the outer surfaces of the lower set of teeth by alternately turning the device about its transverse axis until the proper brushing contact is 25 made with the right and left sides of said set of lower teeth; and finally, when it is desired to change the position of the device preparatory to brushing the lingual surfaces of the lower teeth, the device is turned about its transverse axis to 30 its reverse or end-for-end position where the bristles again point or extend outward, and the ends are respectively swung into the right and 35 left sides of the mouth by swinging or turning the device about its transverse axis.

It is a well recognized fact that tender gums need massaging for toughening them; but experience has proven that the sharp ends of bristles sometimes (if not quite often) scratch, puncture and irritate the gums so that they become sore 40 and infected; so it is desirable to massage the gums or gingivae with the sides of the bristles while brushing the teeth and cleaning between the teeth with the ends of the bristles; and this dual operation can most satisfactorily be accomplished by the angular relation of brush-head-base and brush-heads as shown in Fig. 10. Inasmuch as the setting of teeth differs in different persons' mouths, it is desirable that different angularities be provided, and this may be accomplished by interchanging parts such as 5g and 5h 50 in engagement with the brush-head-base 3g.

In Figs. 7, 8 and 10, the bristles are omitted, the bristle-sockets being shown at 6, but it is understood that all the brush-heads are considered as including bristles. It is also intended that the outer edges of all brush-heads shall be of the semi-cylindrical or rounded form as shown in Figs. 3, 7, 8 and 10, so it will not only eliminate corners that might hurt the gums, but provides a hard 60 smooth rounded surface for helping to massage the gums.

Attaching studs 7 fit into bores 8 and frictionally engage with the walls thereof in securing the brush-heads 5a and 5b in place, and studs 7a 65 frictionally engage with the walls of the bores 8a for frictionally holding the brush-heads 5c, 5d and 5e in place; for as these studs are of springy material, it is only necessary to bend them slightly out of parallel with one another, so the parallel 70 bores force them into parallel and combine therewith for effecting their frictional sliding engagement while permitting them to be removed and interchanged. However, if desired, each engaging pin may be such as shown at 1c (Fig. 9), 75

split approximately throughout its length and having slightly bowed springy sides that define the walls of the split *1d*; and the formation of these split pins may be effected by bending half-round springy wire into the shape shown or into other appropriate shape. In lieu of the attaching studs, dovetail ribs *7r* may be employed, and these may be split at *7s* longitudinally through a tapered part of the rib that normally fits in a tapered part of a groove *8g* of the brush-head-base *3f*. Both the ribs *7r* and walls of the grooves *8g* are somewhat springy, so they effect the necessary frictional engagement for keeping the parts from becoming accidentally displaced while permitting them to be adjusted and interchanged by manually applied force.

Although I have described these embodiments of my invention specifically, it is not my intention to limit my patent protection to these specific details, for the invention is susceptible of numerous changes without departure from the inventive ideas as implied and claimed.

What I claim as my invention is:

1. A tooth-brush comprising a handle member having one end formed with a relatively thin and long and wide brush-head-base, a relatively thin and wide and long brush-head provided with bristles and having one longitudinal thin edge normally fitted against a longitudinal edge of said brush-head-base and provided with means for removably securing it to the latter and for interchangeably securing it to the opposite longitudinal edge of the brush-head-base in a useful correlation with the latter.

2. A tooth-brush comprising a handle member having one end formed with a relatively thin and wide and long brush-head-base, a relatively thin and wide and long brush-head provided with bristles and having one longitudinal thin edge normally fitted against a longitudinal thin edge of said brush-head-base and provided with means for securing it in different adjusted positions along said brush-head-base.

3. A tooth-brush comprising a handle member having a relatively thin and wide and long brush-head-base at one end provided with an elongated socket, and a relatively thin and wide and long brush-head provided with bristles and having one of its longitudinal thin edges against a longitudinal thin edge of said brush-head-base and provided with an inherently springy elongated dowel curved lengthwise and normally penetrating said brushhead-base and exerting pressure against the wall of said socket for frictionally securing said brush-head against accidental displacement while permitting it to be removed manually for replacement by another brush-head when desirable.

4. A tooth-brush including a handle member, a brush-head on an end of the handle and being longer than its breadth, the brush-head having bristles secured thereto and extending from one face thereof, said handle member including a substantially straight part and a compound-curved part which latter is between the brush-head and the straight part of the handle, the plane of said straight part lying substantially in the plane of the free or brushing ends of the bristles, and a second brush-head movably but normally fixed against a longitudinal edge of the first said brush-head and laterally offset therefrom.

5. A tooth-brush which includes a brush-head-base having lateral edges provided with openings, and brush-heads each having lateral edges provided with securing elements to be removably seated in said openings in such relation that the brush-heads can be interchanged and reversed.

6. A tooth-brush which includes a brush-head-base having longitudinally and outwardly tapered lateral edges, and a brush-head having a lateral edge provided with means to secure it interchangeably to the lateral edges of said brush-head-base.

7. The structure defined by claim 6, said means also being such as to permit the brush-head to be adjusted longitudinally on the brush-head-base.

ELMER E. HACHMAN.
